UNITED STATES PATENT OFFICE.

JOHN VLADIMER IRON, OF OAKLAND, CALIFORNIA, ASSIGNOR OF FORTY ONE-HUNDREDTHS TO EUGENE GLATT, OF OAKLAND, CALIFORNIA.

ELEVATOR SAFETY-STOP.

1,163,239.

Specification of Letters Patent. Patented Dec. 7, 1915.

Application filed April 26, 1915. Serial No. 23,851.

To all whom it may concern:

Be it known that I, JOHN W. IRON, a subject of the Emperor of Austria-Hungary, residing at Oakland, in the county of Alameda and State of California, have invented new and useful Improvements in Elevator Safety-Stops, of which the following is a specification.

This invention relates to an elevator safety stop.

One of the objects of the present invention is to provide a simple, substantial, easily applied safety catch or grip for vertically moving, suspended elevator cages or the like which will automatically grip the guide rails in the shaft and stop the cage from descent if one or more of the connected lifting or counterbalancing cables part or give way, thus preventing loss of life and limb and unnecessary destruction of property.

Further objects will hereinafter appear.

The invention consists of the parts and the construction and combination of parts as hereinafter more fully described and claimed, having reference to the accompanying drawings, in which—

Figure 1 is a side elevation of an elevator, showing the application of the invention. Fig. 2 is a plan view of the levers. Fig. 3 is a cross section on line 3—3, Fig. 1. Fig. 4 is a cross section on line 4—4, Fig. 1. Fig. 5 is a section on line 5—5, Fig. 4.

A indicates the guide rails in an elevator shaft and B the cage proper. Pivotedly mounted on top of the cage, as at 2, are four levers, such as indicated at 3, there being one pair on each side. Straddling each pair of levers is a bracket 4, and extending through the top of the brackets are stop or set screws 5, one for each lever. These screws not only form stops which limit the upward movement of the levers, but they are also surrounded by coil springs, such as indicated at 6, the function of which will be hereinafter described.

Suitably secured to the inner end of each lever is a cable 7, and pivotally secured to the outer end of each lever is a rod 8. Suitably secured to the lower end of each rod is a wedge-shaped gripping member 9. The downwardly projecting rods 8 are parallelly disposed, one on each side of the guide rails, and the wedge-shaped gripping members are similarly disposed.

Suitably secured near the lower end of the cage are guide brackets 10, one for each gripping member. These guide brackets are provided with a groove 11 on each side, and each wedge or gripping member is similarly provided with a projecting flange 12 to fit the adjacent groove. The gripping members are thus brought into or out of engagement with the face of the guide rails, when raised or lowered, by means of the rocking movement transmitted through the connected lever 3. The face of each gripping member is preferably provided with sharp teeth, such as indicated at 13, for the purpose of forming an effective grip when thrown into engagement with the rails. In this instance four cables have been provided, two of which may be provided for counterbalancing purposes and two for lifting or lowering the cage. In operation, if one or more of the cables should part or give way it will immediately permit the spring 6 to force the lever in a downward direction against the top of the cage, thus pulling rod 8, with connected gripping member 9, in an upward direction. The inclined face 14 of the connected guide bracket 10 will thus force the gripping member inwardly against the face of the guide rail, thus stopping the cage against further descent and avoiding loss of life and limb and unnecessary destruction to property. If only one of the cables happens to part, it will be seen that only one gripping member will be thrown into operative position. The scraping sound and the stopping of the cage will in this instance give sufficient warning to the operator that one of the cables has parted, thus permitting the necessary repairs to be made before any real damage has been done.

By referring to Fig. 1, it will be seen that the main side frame of the cage has been extended a little below the floor line of the cage, such as indicated at 15. Mounted on the lower end of the extended frame is a pair of guide brackets 16, and mounted a similar distance above the floor line and secured to the side frame of the cage is another pair of guide brackets 17. These brackets are more clearly shown in Fig. 3 and are provided for the purpose of guiding or holding the cage against side thrust in the shaft when one or more of the gripping members are thrown into operative position. While the gripping members, with

connected guides, have been shown as mounted near the lower end of the cage, it is obvious that they may be placed near the upper end or at any other suitable point.

5 A cage constructed as here shown is substantial in construction and the connected safety stop here provided is so constructed that it may be attached to practically any cage now in use. The provision of the 10 springs 6 produces an automatic action which will instantly throw the gripping members into operative position when one or more of the cables part.

15 The materials and finish of the several parts of the apparatus are such as the experience and judgment of the manufacturer may dictate.

I wish it understood that various changes in form, proportions and minor details of 20 construction may be resorted to within the scope of the appended claims and that I do not wish to limit myself to the specific design and construction here shown.

25 The upper ends of rods 8 are preferably attached to levers 3 by means of U-shaped links 20. This permits the rods to be raised or lowered by means of nuts 21 to adjust the position of the gripping members with 30 relation to the guide rails. The wedge-like gripping members can thus be raised into a position where a slight movement of the connected lever when the cable breaks will throw the gripping member into engagement with the rail. The inner ends of the 35 levers or the ends to which the cables attach are preferably weighted or constructed sufficiently heavy to overbalance the weight of the connected rods and wedges. The springs 6 are thus merely provided for the 40 purpose of kicking or starting the arms to perform their function and are, therefore, comparatively short and in no way connected with the arms.

Having thus described my invention, what 45 I claim and desire to secure by Letters Patent is—

1. The combination with the cage and

guide rails in an elevator shaft, of a pair of levers pivotally mounted on each side of the cage, a cable attached to the inner end of 50 each lever, a rod attached to the outer end of each lever, said rods extending down the sides of the elevator parallel with the guide rails, a wedge-shaped gripping member secured on the lower end of each rod, a guide 55 bracket secured on the cage, one for each gripping member, to force said members into or out of engagement with the guide rail when raised or lowered by the connected lever, a bracket straddling the inner ends 60 of each pair of levers, stop members to limit the upward movement of the levers, and springs interposed between the brackets and levers to depress the levers when the cables 65 part.

2. The combination with the cage and guide rails in an elevator shaft, of a pair of levers pivotally mounted on each side of the cage, a cable attached to the inner end of each lever, a rod attached to the outer end 70 of each lever, said rods extending down the sides of the elevator parallel with the guide rails, a wedge-shaped gripping member secured on the lower end of each rod, a guide bracket secured on the cage, one for each 75 gripping member, to force said members into or out of engagement with the guide rail when raised or lowered by the connected lever, a bracket straddling the inner ends of each pair of levers, stop members to limit 80 the upward movement of the levers, springs interposed between the brackets and levers to depress the levers when the cables part, and guide members secured to the cage above and below the wedge guides in close 85 proximity to same and engageable with the sides of the guide rail.

In testimony whereof I have hereunto set my hand in the presence of two subscribing witnesses.

JOHN WLADIMER IRON.
